ROCK BIT

Wallace D. McEachern, Odessa, Tex.

Application March 23, 1953, Serial No. 344,013

3 Claims. (Cl. 255—313)

This invention relates to a method and means of lubricating rotary cone rock bits and more particularly, but not by way of limitation, to a method and means of cleaning and cooling a rock bit by concentration of a lubricating fluid within the bit.

As is well known in the art, the lubrication of the rotary cone rock bits utilized in rotary drilling of oil wells is usually provided through mud and water from a pump at the surface of the well circulating through the drilling string and discharged from the rock bit at the bottom of the well bore. The fluid circulation in rotary drilling has two definite purposes, one is to lubricate and cool the bearings of the cutters from the heat generated during rotation thereof, and the other is to remove the cuttings which are being ground out of the well bore.

It has been found that in certain geological formations the rotation of the rock bit substantially pulverizes the strata being drilled, thereby causing a considerable amount of dust which will accumulate in the bearings, or the cone teeth and must be removed to prevent locking of the cutter cones. While liquid has been used in the past for removing cuttings from well bores, the use of compressed air to blow out pulverized cuttings to prevent accumulation of dust usually behind the cones and the bearings has been satisfactory. The compressed air utilized for cleaning the cones and removing the pulverized cuttings, also acts as a lubricator and cooling medium for the bearings from the heat generated by the cone rotation. The temperature generated by the rock bits may be as high as five to six hundred degrees Fahrenheit which obviously causes the bearings to wear much faster, and reduce the efficiency of the bit in general.

It is known in the art that air has been used for a cooling and cleaning medium in rotary drilling. Usually the size of the opening of the longitudinal passageway in the center of the bit shank has been reduced and then providing small openings leading into each cone. Also the opening has been enlarged to maximum diameter. However, both methods have proven unsatisfactory to efficiently clean the cones and cool the bearings at the same time.

The present invention is generally concerned with the utilization of a baffle plate placed beneath the cones of a multiple rotary cone bit, such as a two or three cone bit being utilized today in drilling operations. It is to be understood that the baffle may be used with a bit having any number of cones by simple modification. The baffle plate is constructed to direct the air from the drill string, and enter the longitudinal passageway of the bit shank where it is directed in a manner to concentrate the projection of the air for a uniform over-all distribution throughout all the cones, thereby providing an efficient cooling of the bit, as well as cleaning and removing the pulverized cuttings from the bit and onto the top of the well.

It is an important object of this invention to clean a roller cone rock bit in such a manner that all cuttings

2

accumulated within the bit are efficiently removed therefrom along with a simultaneous cooling of the bit.

And still a further object of this invention is to direct compressed air through a roller cone rock bit in such a manner that any accumulation of dust within the teeth or bearings of the bit from pulverized cuttings is removed in an efficient and expeditious manner simultaneous with a cooling of the bit proper.

Another object of this invention is to utilize a pressure fluid as a medium for cleaning accumulated pulverized dust cuttings from a rotary rock bit in such a manner that the heated bearings are simultaneously cooled at a point conterminous with the jointure of the bit cone and supporting spindle so that the fluid is then directed from the rear of the cones forward through the bit.

Other objects and advantages of the invention will be evident from the following detailed description, read in conjunction with the accompanying drawings, which illustrate my invention.

20 In the drawings:

Figure 1 is a perspective view of a well drill with certain parts broken away for illustrating the invention.

Figure 2 is a detail plan view of the rock bit with the cutter cones removed for purposes of better illustrating 25 the baffle plate.

Figure 3 is a modification of the baffle plate.

Referring to the drawings in detail, and particularly Fig. 1, the rock bit 2 is disclosed in up-ended position from that of its drilling position for clarity. The rock 30 bit 2 comprises the usual tapered shank 4 adapted to operate by threaded engagement with a drill collar or drill string (not shown). The tapered shank is integral with a head 6 having a plurality of extended legs 8, 10 and 12 in the usual manner. The rock bit is constructed 35 with the usual clefts or notches 14 provided between each of the legs. The tapered shank is provided with a longitudinal passageway 16 having a reduced diameter at 18 extending into a discharge outlet 20. The legs are each provided with the usual inwardly inclined shafts 22 for 40 receiving the roller cutter cones 24 secured thereon by suitable bearing members in a manner not shown. As is clearly shown in Fig. 1, two of the cones 24 are partially cut away, along with a portion of the legs 8 and 10 for purposes of illustration. The roller cutter cones 45 24 have the usual chisel teeth 26 and are preferably of the interfitting type, although not necessarily limited thereto.

The continuous rotation of the cutter teeth pulverize 50 the cuttings from the geological strata to the extent that compressed air can be directed through the usual longitudinal passage 20 for blowing the cuttings to the top of the well. However, it is necessary to cool the bearings and the cutter teeth, thereby reducing the temperature 55 of the heat generated by the rock bit, sometimes running as high as 500 or 600 degrees Fahrenheit. In order to utilize compressed air for removal of the cuttings with a simultaneous cooling of the cutter teeth and bearings, it is necessary to concentrate the direction of the air, into 60 and through, the rock bit. In order to provide this concentration, a baffle plate 28 is provided and is preferably disposed within the rock bit 2 during the manufacturing assembly of the bit prior to the mounting the cutter cones 24 on the shanks 22.

As is clearly shown, the plate 28 is of a substantially 65 triangular configuration having a central aperture 30 of a smaller diameter than the reduced bore 18 for purposes as will be hereinafter set forth. The apex 32 of each preferably rounded corner of the triangle, Fig. 2 (although they may be pointed, Fig. 1), is adapted to be 70 disposed in the notch 14 between the leg members of the rock bit 2 so that positioning of the plate 28 within the bit is facilitated. The plate 28 is disposed in such a

manner that the apexes 32 thereof engage the bottom of the notches 14 and abut inner surfaces of the leg members 8, 10 and 12. Furthermore, the plate 28 is slightly spaced from the bottom or inside portion 34 of the head 6 because of the slight curvature of the inside portion 34, as shown in Fig. 1, thereby providing a chamber 35 between the head 6 and the plate 28 for dispersement of the air moving through the bore 20 and into contact with the plate 28, as will be hereinafter set forth. The plate 28 is preferably welded to the inner surfaces of the leg members 8, 10 and 12 at points 33 adjacent the notches 14 in any well known manner (not shown) whereby air cannot flow around the plate 28 through the notches 14. It is to be understood that the securing of the plate to the bit is not limited to welding, but may be secured by any suitable means. The triangular plate 28 is provided with a plurality of recesses or notches 36 along each marginal edge thereof so that with the plate 28 in position, the notches are substantially centrally disposed against the inner periphery of each of the legs 8, 10 or 12 as is clearly shown in Fig. 2. A portion of the air flowing through the reduced bore 18 will be deflected by the plate member 28 since the central bore 30 of the plate is of a smaller diameter than the bore 18. Thus, a portion of the air will be deflected into the chamber 35, wherein the air will tend to seek the line of least resistance and flow through the notches 36, as will be hereinafter set forth.

After the roller cutter cones 24 have been mounted on the shanks 22, it will be apparent that a notch 36 is disposed beneath a cutter cone and substantially adjacent the heel teeth of each cutter cone 24. The disposition of the edge-wise slots 36 substantially conterminous with the back portion of the cutter cones 24 places them in proximity of the bearing recess for a purpose as will be hereinafter set forth. The aperture 30 substantially conforms to the diameter of the small bore 20 in the head 6 of the rock bit 2.

Operation

In operation, compressed air from any suitable compressor (not shown) at the surface of the well is directed through the drill string and into the longitudinal passage 16 and through the passageway 18 where a portion of the air will be deflected by the plate 28 because the aperture 30 is of a smaller diameter than the bore 18. The deflected air is directed between the bottom of the baffle plate 28 and the face 34 of the head 6, and hence discharged through the edge-wise slot portions 36, since the air will tend to seek the line of least resistance, and escape from the chamber 35 through the openings 36. It will be apparent that the edge-wise slots may vary in inclination and while it is preferable to incline the slots preferably between forty-five or sixty degrees for directing the air upwardly through the individual cutter cones 24, the invention is not limited to any specific angled inclination of the slots 36.

The diverting or channeling of the air to the back teeth or heel section of the cutter cone where the spindles 22 and the cutters are joined facilitates the cooling of the cones and bearings of the rock bit 2. Furthermore, the concentrated direction of air provides for cleaning of the cones by preventing accumulation of pulverized cuttings between the interstices of the teeth 26 on the interfitting cone members. The stream of air is channeled by the baffle plate to the point of attachment to the cutter cones 24 and by removing any excess accumulation of dust prevents locking of the cones, thereby providing free rolling thereof at all times.

In addition to the diverting of the air by the baffle plate 28 through the edge-wise slots 36, a portion of the air discharges through the aperture 30 in the center of the baffle plate 28 and co-mingles with the air moving from beneath the cutter cones outwardly therethrough, thereby materially assisting in removing all cuttings and accumulated dust from the rock bit to the outside of the drill

pipe in order to be displaced to the surface of the well. It will be apparent that use of the adapter baffle plate 28 is not limited to air, and water or other fluids may be utilized if desired for effecting a cooling and removal of cuttings from the rock bit. As heretofore mentioned, the inclination and size of the edge-wise slots 36 is variable, and depends to a great extent upon the formation in which the bit is drilling. If air is used entirely, the slots can usually be smaller and of less degree of inclination, whereas if the cleaning and cooling fluid is water, the slots may be larger and of greater incline. It will thus be seen that the baffle plate provides flexibility of control in variable sizes for the same size rock bit, and the adapter plate 28 can be made in a number of sizes corresponding to the size rock bit with which it is desired to be used. It will be understood that the variations of the marginal slot control of the adapter plate 28 is also dependent upon geological structure as stated, such as, for example, in a sticky, gummy surface it would be preferable to use larger slots, whereas in a hard chert formation the slots may be of less size and less incline. Furthermore, the pressure depending upon the size of pump and the capacity of the well would have some bearing upon the size of the slots for directing the fluid through the bit. It will be apparent that the diversion of the compressed air to the back side and beneath the heel teeth of each cutter cone is one of the outstanding novel features of the invention.

Although the adapter baffle plate 28 has been shown as a one piece construction for use in manufactured bits being assembled, it will be apparent that in bits already assembled a baffle plate utilizing the marginal edge slots 36 may also be secured beneath the individual cones. It is only necessary to cut the triangular baffle plate 28 into a plurality of sections 40, preferably three (Fig. 3), but not limited thereto, so that each section 40 will slip through a notch or cleft 14 between the legs and form a baffle above the longitudinal passageway 16. Of course, each individual section plate 40 has a marginal edge slot 36 adapted to be disposed beneath the heel teeth of each cone 24 for the purpose as previously set forth. One adaptation of separate sections is shown in Fig. 3. However, it is not limited to that particular disclosure and may be modified to variable extents as long as the edge slots 36 are disposed at the rear of each cutter cone 24 and beneath the cone. Also the aperture 30 should be in substantial alignment with the longitudinal bore 20. These individual baffle plates may be welded, or secured in any suitable manner to the face 34 of the head 6 and function to divert the compressed air through the marginal slots into contact with the back side and heel teeth of the individual cutter cones 24.

From the foregoing, it will be apparent that the present invention contemplates modification of a rotary rock bit having a plurality of cutter cones thereon by disposition of a baffle plate between the bit head and the cutter cones for diverting or channeling compressed air or similar fluid through the center of the bit and also at the base of each cone, thereby concentrating the flow of the compressed air at the point where locking is prevalent due to accumulated dust or the like in order to remove the dust with a simultaneous cooling of the bearings. Furthermore, the compressed air moves from the base through the interstices of the teeth in conjunction with the air moving through the central portion of the bit in order to effect a complete cooling and cleaning of the bit throughout.

Changes may be made in the combination and arrangement of parts as heretofore set forth in the specification and shown in the drawings, it being understood that any modification in the precise embodiment of the invention may be made within the scope of the following claims without departing from the spirit of the invention.

What is claimed is:

1. In a roller rock bit comprising a head, a plurality of spaced leg members provided on the head, a conical

cutter mounted for rotation on each of the legs, a plurality of teeth on the cutters, a longitudinal passageway in the head providing a circulation of fluid through the bit, a baffle plate mounted above the conical cutters and having the edge portions thereof disposed adjacent the heel teeth of the cutters, a plurality of elongated slots provided on the edge portions of the baffle plate wherein one of the slots is disposed adjacent the heel teeth of a cutter cone, said baffle plate spaced from said head and having the corners thereof adjacent the legs for cooperation therewith to provide a compartment between the plate and head, said compartment providing communication between the slots and the longitudinal passageway for directing a portion of the fluid discharging therethrough to the slots and into contact with the leg members wherein the air is diverted to and through the cutter teeth, and an aperture provided in the baffle plate in substantial alignment with the longitudinal passageway for directing the remaining portion of the fluid proximity with the apex of the cutter cones, and said baffle plate member secured to said head member whereby the edge portions are sealed adjacent the leg members in order that the fluid will pass only through the plate aperture and slots.

2. In a roller rock bit comprising a head, a plurality of spaced leg members provided on the head, conical shaped cutters mounted for rotation on each of the legs and having a plurality of interfitting teeth, a longitudinal passageway in the head communicating with the cones and providing circulation of compressed air therethrough, an attenuated segmental baffle plate of substantially triangular configuration mounted above the cutter cones and having the edge portions thereof disposed adjacent the heel teeth of the cutter cones, an aperture provided in the baffle plate in alignment with the passageway, a plurality of edge-wise slots provided in the segmental baffle plate wherein one slot is disposed adjacent the rear base portion of a cone, said baffle plate spaced from the head in order to direct a portion of the compressed air to the slots and into contact with the base of the legs

wherein the legs will divert the air to the cutters for cleaning any accumulated pulverized cuttings therefrom simultaneous with a cooling of the bearings, said plate secured to said head whereby the aperture provides for discharge of the remaining portion of the air into the proximity of the apex of the cutters.

3. In a roller rock bit comprising a head, a plurality of spaced leg members provided on the head, a conical cutter mounted for rotation on each of the legs, a plurality of teeth on the cutters, a longitudinal passageway in the head providing for circulation of fluid through the bit, an attenuated baffle plate of substantially triangular configuration mounted above the conical cutters and having the edge portion thereof adjacent the heel teeth of the cutters, a plurality of elongated slots provided in the baffle plate along the edge portion thereof wherein one of the slots is disposed adjacent the heel teeth of the cutter zone, said baffle plate spaced from said head and cooperating with the legs to provide a compartment therebetween, said compartment providing communication between the slots and the longitudinal passageway for directing a portion of the fluid discharging therethrough to the slots and into contact with the legs for diversion to and through the teeth, an aperture provided in the baffle plate in alignment with the longitudinal bore for directing the remaining portion of the fluid into the proximity of the apex of the conical cutters, said baffle plate secured to the head with the edge portions sealed whereby the fluid will pass through the aperture and slots only.
